BENJAMIN S. BERNHARD, OF BOSTON, MASSACHUSETTS.

DOOR CLOSER AND CHECK.

Application filed February 1, 1926. Serial No. 85,159.

One of the objects of my invention is to provide a door closer and check to be embedded in a door or the like and in the support therefor and of such small dimension 5 in the direction of its extension into the door and support that the device will not undesirably interfere with the construction of the support as, for example, with the plastering or with the construction of the door 10 or the like as, for example, with parts beyond that style which is adjacent to the support, the desirability of such small extension being well known to those skilled in the art.

Another object is to provide a door closer 15 and check of very great power.

Other objects will be pointed out below.

A feature of my invention is that the piston moves vertically with a consequent 20 saving of space in a direction extending into the door or support, the piston being capable of being mounted to move within the door or within the support.

Another feature of my invention is a worm 25 to engage and operate the piston and preferably the axes of the worm and of the piston are vertical and identical.

Another feature is automatic mechanism 30 for relieving strain on certain of the working parts and on the pivotal connection between the door and support.

Another feature is a mechanism including a flexible member to prevent undesired closing of the door or the like and preferably this member acts frictionally to retard 35 undesired swinging.

Other features are guiding mechanism for the door-closing chain and tension devices for that chain.

Other features will be pointed out below.

In the drawings

Figure 1 is a central vertical section of a door closer and check embodying my invention;

Figure 2 is a portion of the sectional view of Figure 1 but with the piston and springs in positions different from those of Figure 1;

Figure 3 is a section on line 3-3 of Figure 1;

Figure 4 is a partial section on line 4-4 of Figure 1;

Figure 5 is a view partly in plan and

partly in section on line 5-5 of Figure 1 with the door open;

55

Figure 6 is a fragmentary plan and section more fully described below;

Figure 7 is an elevation of part of the guiding means;

Figure 8 is a bottom view of part of the 60 guiding means;

Figure 9 is a partial plan and partial section on line 9-9 of Figure 1 with the door open;

Figure 10 is a sectional detail on line 65 10-10 of Figure 9;

Figure 11 is a fragmentary end elevation, partly in section, showing particularly parts of the guiding means; and

Figure 12 is a front elevation of the housing.

Door 1 is hinged to support 2 which has the trim 3 and plastering 4. The support, in the form of my invention shown, is recessed to receive casing 5 which has a checking chamber 6 within which moves piston 7, the latter having flange 8 guided by guide rods 9 and 10, which have lugs at each end, the lugs at the bottom being press fitted into the casing and the lugs at the top entering 75 suitable openings in plate 11 which is held to the casing 5 by screws 12, gasket 13 being interposed if desired.

Springs 14 and 15 surround guide rods 9 and 10 and abut at their tops against plate 85 11 and at their bottoms against flange 8 and tend to force piston 7 downwardly.

The piston 7 is interiorly threaded to engage worm 16, the shaft 17 of which extends upwardly into a cylindrical bore in flange 90 18 of plate 11, said shaft having integral collar 19 bearing against thrust washer 20, the latter bearing against the bottom edge of flange 18. The worm member at the bottom thereof has pressed into it at its centre 95 a hardened steel ball 21 which turns upon hardened steel disk 22, thus providing a single point bearing of very low friction and great durability. The shaft is provided at its upper end with a drain groove and a packing groove and also with teeth 23 which extend through opening 24 in plate 11 and engage rack 25. These teeth 23 extend upwardly to the top of the shaft 17 in reduced form and upon their reduced portions 105 is splined sprocket 26 to be described below.

The top of the shaft is accessible from the outside through opening 27 in the cover which will be described below so that a suitable tool may be applied to the top of the shaft for installation purposes.

Casing 5 is substantially filled with suitable fluid, such as oil, and in order to permit ready passage of fluid from chamber 28 to the space 6 I provide conduits 29 and 30 in guide rod 10, conduit 29 leading from chamber 28 to conduit 30 and the latter leading to conduit 31 in casing 5. Conduit 31 is controlled by ball valve 32 in chamber 33, from which conduit 34 leads to chamber 6. Guide rod 10 is exteriorly flattened at 35 for permitting free passage of the liquid between it and flange 8 to the chamber 6 at the beginning of the up stroke.

When the piston is in the position of Figure 2 on the down stroke the flow of liquid from space 6 is controlled by valve 35^a in its passage through conduits 36, 37, 38, 37^a and 39 to chamber 28 except that if valve 40 is open fluid may flow through conduits 36, 41, 42 and between the flattened portion 43 of the piston and the wall of chamber 6 and thence to chamber 28. Even if valve 40 is open the unflattened portion of the piston will close conduit 42. In order to prevent leakage the lower lug of guide rod 9 is a very tight fit in casing 5. In order to prevent leakage from conduit 41 past valve 40 and up through conduit 39 I provide a sleeve 44 pressed tightly into the casing 5, and further provide suitable packing 45 to prevent leakage to the outside of the casing.

A sleeve 46 is press fitted into the casing and forms a conduit leading to conduit 39 and thence to chamber 28, one end of the sleeve being normally closed by ball 47 which is held in place by spring 48, the latter being held under predetermined pressure by nut 49. If the pressure in chamber 6 exceeds said predetermined pressure as for example by pressure caused by attempting to force the door shut then said ball 47 will be forced off its seat and the strain on certain of the working parts and on the pivotal connection between the door and support will be automatically relieved by escape of the fluid through conduit 39 to chamber 28 and at that time escape of fluid to the outside of the casing is prevented by packing 50 held in place by nut 51. When the excessive pressure is relieved the ball 47 will reseat itself automatically.

Sprocket 26 is, as above explained, splined to the shaft 17 and is in engagement with chain 52, one end of which is pivoted to stud 53 having a flange 54 which forms one abutment for compression spring 55 the other abutment of which is the inwardly extending shoulder 56 of the housing 57 which is embedded in the door 1 in the form shown,

said stud 53 having a boss 58 which has a perforation 59 to receive one end of coiled spring 60 the other end of which is looped over pin 61 mounted in the housing 57, said spring 60 acting as a take-up for the chain 70 as will be more fully described below, the stud and two springs 55 and 60 being mounted within the bore 62 of the housing 57.

The chain 52 extends from stud 53 through opening 63 in the casing and runs on shoe 75 64 which is in the form of a block held in position with relation to plate 11 by spacing member 65 and held immovably by screw 66 which engages plate 11, shoe 64 abutting against a wall of opening 63 as 80 appears clearly in Figure 5.

From shoe 64 the chain extends into engagement with sprocket 26 and any tendency to slip off the teeth of the sprocket would be prevented by cover 67 which is 85 held in place by screws 68. The chain, as it moves to the right in Figure 5, is disengaged from the sprocket 26 by surface 69 of plate member 70 and then passes between said plate member 70 and semi-circular block 71 to sprocket 72 and from sprocket 72 the chain moves to the left in Figure 5 between plate member 70 and cover 67 and thence into engagement with the teeth of sprocket 26 (at the top in 95 Figure 5), continuing to the left in Figure 5 for the rest of the travel of the chain. Block 73 is fastened to plate 11 by screw 74 and holds the chain up in position for engagement with the teeth of sprocket 26 (at the 100 top in Figure 6). Torsion spring 75 has one end bent to engage sprocket 72 and the other end bent to engage shaft 76 upon which sprocket 72 is free to turn, said shaft being reduced at its lower end and threaded 105 to engage plate 11 and being supported at its upper end by fitting an aperture in the cover 67, this upper end having a slot for a screw driver in which slot rests one end of spring 75.

The description just above given is of the movement of the chain when the door is being closed.

Plate 77 is integral with parts 70 and 71 and consequently holds part 71 in place and fitting closely within the walls of cover 67 holds itself and parts 70 and 71 in place.

Rock 25 is kept in proper relation to teeth 23 by the wall of cover 67 and is prevented from tilting away from said wall by pin 120 78. Pivotedly connected to the rock 25 is one end of a flexible member 79 in the form of a coiled spring, the other end of said flexible member having a button 80 provided with a groove in which is placed a split 125 ring 81 having frictional engagement with the bore 82 of housing 57, the purpose of this frictional engagement being to retard undesired swinging. At the closed end of bore 82 is a resilient disk 83 preferably of 130

leather to form a yielding abutment for the button 80. The bore 82 is preferably flared at 84 to facilitate the bending of flexible member 79 and is preferably flared at 85 to give additional space for the flexible member. Pins 86 and 87 prevent button 80 from leaving bore 82 but do not interfere with the movement of the coils of the flexible member, said pins being inserted in the housing 57 after the button 80 has been inserted in the bore 82.

I have described my piston and the fluid chamber as embedded in the support but they and their casing might be embedded in the door or the like and in such case the housing might be embedded in the support.

When the door is closed no part of my device is visible from either side of the door. When the door is started in its opening movement the chain 52 moves through the opening 63 in contact with shoe 64, semi-circular block 71 guiding each link of the chain as such link passes said block into early engagement with the sprocket 26, that is to say, into engagement with a tooth of the sprocket additional to those teeth which would be engaged without such block so that such early and additional engagement overcomes the normal tendency of the chain to walk away from the sprocket which might result in jamming of the chain against the wall of the cover.

During the closing movement the curved portion 69^a of plate 70 acts to disengage the chain from sprocket 72, the latter acting to lay away the chain in proper position for use.

During the opening movement the torsion spring 75 is wound up and tends therefore to prevent slack and is put in condition to take up slack on the return movement. This opening movement rotates sprocket 26 and shaft 17 and consequently worm 16 and thereby raises piston 7 on the guide rods and compresses springs 14 and 15 and during this raising the fluid enters chamber 6, passing through conduits 29, 30, 31 and past ball valve 32 which drops to permit such passage and thence through conduits 33 and 34 to chamber 6. A relatively small amount of fluid may pass through conduits 39, 37^a, 38, 37 and 36 to chamber 6. During the opening movement the rack 25 is moved to the left in Figure 9 by teeth 23, the rack moving slower than the chain so that when the door is in the position of Figure 9 the button 80 will be spaced from disk 83, the flexible element 79 accommodating itself to the opening of the door.

When the door is released by the operator the springs 14 and 15 act to force the piston down which forces fluid from chamber 6 through conduit 34 into conduit 33 and thereby forces ball valve 32 against its seat.

The main control valve 35^a is adjustable

and controls the entire closing if adjustable valve 40 is closed, the fluid, during the closing, escaping from chamber 6 through conduit 36 past the open valve 35^a and through conduits 37, 37^a, 38 and 39 back to chamber 28. If valve 40 is open; as shown, then, near the end of the closing movement the fluid, which is in conduit 36 and conduit 41 and around sleeve 46 and is prevented from escape by the wall of piston 7, may, when the flattened portion 43 comes opposite conduit 42, escape past the piston 7 into chamber 28, this being particularly useful in connection with the latching because it reduces the resistance to the springs 14 and 15 at the time of latching. If this additional force at the time of latching is not desired valve 40 may be permanently closed, such permanent closing of valve 40 having no effect of impairing the utility of the device if such additional force at latching is not desired.

Spring 48 is normally adjusted to hold ball 47 against its seat as above explained but it may be forced off its seat to relieve the pressure by escape of fluid through conduits 37^a and 39 and around sleeve 44 to chamber 28 if undesired strain is put on certain of the working parts and on the pivotal connection between the door and the support as, for example, by wind or by pushing on the door by the operator, such relief of pressure being available until the piston 7 closes conduit 46 whereupon the checking action will be fully in effect and at such time there will be no occasion to provide such relief.

When the door has been opened through approximately 180° the outermost link of the chain will rest against one outer edge of shoulder 56 and said link then becomes a sort of lever which tends to move stud 53 outward from the housing and this tendency is yieldingly resisted by compression spring 55 thereby relieving excessive tension on chain 52. If the door, in its closing movement, should move faster than the chain, the latter and stud 53 and spring 55 will move inward in the housing, spring 55 being moved inward because the chain link is wider than the internal diameter of spring 55. This inward movement is caused by extension spring 60 and when the chain becomes taut with relation to the door, the spring 55 will act between collar 54 and shoulder 56 as a shock absorber.

During the closing movement split ring 81 acts frictionally to retard undesired swinging. In case of the action of any external force, such as wind, tending to slam the door closed the button 80 will engage disk 83 and prevent closing until the desired closing is accomplished by the closing and checking mechanism.

Among the advantages of my device I may point out that it is very simple and

compact and this compactness is largely contributed by my use of the worm disclosed which is of such a pitch that it actuates the piston on the upstroke of the latter, and 5 is actuated by the piston on the downstroke of the latter. Another feature of great practical importance is that with my vertically moving piston the checking chamber is at 10 the bottom of the casing and consequently there is no danger of the formation of air pockets.

What I claim is:

1. A device of the character described comprising a door member or the like; a 15 supporting member therefor; means to close the door including a vertically movable piston embedded in one of said members; a cylinder wall cooperating with said piston; means to prevent relative angular movement between the piston and wall; and means acting on the end of the piston 20 to check the closing action of the closing means.

2. A device of the character described comprising a door member or the like; a 25 supporting member therefor; means to close the door including a rotatable worm having a vertical axis and actuated to contribute to the closing, a vertically reciprocating piston 30 directly engaging said worm, the pitch of the worm being such as to actuate the piston in its movement in one vertical direction and such that the worm is actuated by the piston in the movement of the latter in the 35 other vertical direction, said piston and said worm being embedded in one of said members; a cylinder wall cooperating with said piston; means to prevent relative angular movement between the piston and wall; and fluid means to check the closing action 40 of the closing means.

3. A device of the character described comprising a door or the like; a support 45 therefor; means to close the door including a sprocket and a chain cooperating with said sprocket, said chain operatively connecting the door and support; means to check the closing action of the closing means; and means additional to said checking means to 50 stop undesired closing of the door.

4. A device of the character described comprising a door or the like; a support 55 therefor; means to close the door including a flexible element having a free end, and a rotary element; means to guide the free end of the flexible element into engagement with the rotary element; and means to check the closing action of the closing means.

5. A device of the character described 60 comprising a door or the like; a support therefor; a flexible element connecting the door and support; a rotary element cooperating with the flexible element; an additional rotary element to lay away the flex-

ible element in proper position for use; and 65 means to disengage the flexible element from said additional rotary element.

6. A device of the character described comprising a door or the like; a support therefor; a flexible element connecting the 70 door and support; a rotary element cooperating with the flexible element; and resilient means to lay away a portion of the flexible element in proper position for use.

7. A device of the character described 75 comprising a door or the like; a support therefor; a flexible element connecting the door and support; a rotary element cooperating with the flexible element; and an additional rotary element and a coiled spring to 80 lay away a portion of the flexible element in proper position for use.

8. A device of the character described comprising a door member or the like; a supporting member therefor; checking 85 means mounted in one of said members; a flexible element connecting the door and support; and resilient means in the other of said members acting as a take-up for the flexible element.

9. A device of the character described comprising a door or the like; a support therefor; means to close the door; means to check the closing action of the closing means; and means, operatively connected 95 with the closing means and connected at all times to the door and support, to prevent undesired complete closing of the door, said last-mentioned means being movable automatically to permit complete closing when 100 desired.

10. A device of the character described comprising a door member or the like; a supporting member therefor; means to close the door; means to check the closing action 105 of the closing means; a housing in one of said members; and means to prevent undesired complete closing of the door, said last-mentioned means being movable automatically to permit complete closing when desired and including an element having sliding and frictional engagement with the interior of said housing, said preventing means being operatively connected with the closing means.

11. A device of the character described comprising a door member or the like; a support therefor; means to close the door including a flexible member connecting the door and support, a worm, and a piston directly engaging said worm, the latter actuating the piston to move the piston in one direction and the worm being actuated by the piston in the movement of the piston in the other direction; and means to check the 120 closing action of the closing means.
